ATTORNEY

UNITED STATES PATENT OFFICE.

THOMAS HARVEY POPE, OF BROOKLYN, NEW YORK.

AMUSEMENT GAME.

1,416,506.

Specification of Letters Patent. Patented May 16, 1922.

Application filed March 11, 1920. Serial No. 365,126.

To all whom it may concern:

Be it known that THOMAS HARVEY POPE, a citizen of the United States, residing at Brooklyn, in the county of Kings and State 5 of New York, has invented certain new and useful Improvements in Amusement Games, of which the following is a specification.

My invention relates to amusement games for study and pastime, wherein it requires 10 attention and persistency to accomplish the successful corraling of the spheres in proper corners.

One object of my invention is to produce a small game that may be carried in the 15 pocket, so that its use may be not be limited in any way whatsoever.

Another object is to produce such game, easy to manufacture, reasonable in cost, in other words, to make a simple, neat, cheap 20 and attractive game that will command the interest and attention of every one who sees it.

The object of the invention is to get the small balls from the center of the container 25 and hold three balls in each of the opposite corners behind the partitions.

The invention as at present preferred is illustrated in the accompanying drawings, in which—Figure 1, shows the game as it 30 appears when resting on a flat surface; Figure 2, a cross sectional view taken on lines 2—2 of Figure 1; Figure 3, a detached detail of the floor, showing the position of the partitions in opposite corners; Figure 4, a 35 plan view looking into the container, showing the pillows in the opposite corners; Figure 5, is a modified construction of Figure 3; Figure 6 is a view of one corner showing the pillow in place and the slant of the floor towards the opening, and Figure 7 40 shows a modified way of accomplishing the invention.

The same reference characters designate the same parts throughout the several views.

45 The game herein shown looks so simple that at the first glance, the person picks the same up, reads the instructions and at once sets about to accomplish the task, the simplicity lies in the fact that the game is very 50 deceptive to the eye, therefore the difficulty of corraling three of the restless little spheres while trying to get the other three in the opposite corner.

55 Referring to Figure 1, the receptacle or container 7, which is in the present case preferably rectangular in shape, is pro-

vided with outer walls 8, 9, 10 and 11, with the bottom 12 secured thereto. 13 and 14 are pillows that are in this instance made secure in their respective corners, so that 60 when the floor 15 is placed thereon it will cause these triangular portions of the floor at these particular points to assume a different angle or slant from other portions of the same, particularly the corner portions of the 65 flooring opposite to that containing the pillows, the whole flooring presenting a smooth rolling or undulated surface for the spheres to roll over.

It is preferred to give the floor surface 15 70 a twisting rolling undulated surface that will have a gradual sloping incline or decline at any of its various points therein, such unevenness being gradual and ununiform, with the end in view to make it 75 harder for the performer to divide the number of little spheres some behind one compartment and the balance in the other. The floor may be provided with suitable slits 16, 17 and 18 in which may be secured a number of partitions 19, 20 and 21. It is preferred as has been noted to provide partitions of the same material as that of the floor, such for instance as will afford a little 80 resistance, being in this instance about a 3 85 ply paper, as the best results can only be attained by having the balls bounce and bound around by their contact with the partitions, and their arrangement such that they divide the opposite corners into triangular 90 95 corrals for the spherical bodies that I will describe further on. Such angular corrals being formed by the sides of the receptacle and the three partitions so arranged that, two of the partitions are located in the forward slits, and being in alignment and spaced apart, permits of a passage way or opening 22, while in the rear is placed another partition 21 which extends across the 100 opening 22, and thereby preventing the free movement of the spherical bodies towards the exit 22. The forward partition or partitions 19 and 20 may only be secured to one side of the slits 16 and 17 when the pillows are used, thus leaving the other portions to assume any angular position by reason of the pillows 13 and 14. As is noted in the drawing each of the opposite corners are provided with like partitions, therefore it is 105 not necessary to describe each corner separately, the description of one corner with its partitions will suffice for the opposite 110

corner. It is to be understood that the partitions one and all are of such resilient material that when the balls come in contact with them accidentally or otherwise in trying to corral them, they will bounce and bound away, making it very difficult for the performer or operator to control the movements of the many spheres. It matters not whether the pillows are used, as long as the 10 flooring is given that smooth rolling uneven surface over which the many balls roll, both within and without the partitioned compartment, together with the fact that the partitions that extend above the floor are lively, 15 which is absolutely necessary, as has been noted, as to cause the accomplishment of the game to be more hazardous, to the great interest and amusement of the performer.

It is preferable to use six steel balls 23, 20 which are placed in the container before the cover 24, which is preferably of glass and is secured in place on the side walls 8, 9, 10 and 11, and a binder pasted about it, and the side walls, which completely closes 25 the container, by this means it not only closes, but secures all the parts together. By such closure the game is made attractive in appearance.

By reason of the partitions 19 and 20 being in alignment, it forms a triangular compartment or corral, and by reason of this portion of the floor resting on the pillows 13 and 14, and being free to assume any position it causes the triangular portions 25, 26 and 27 to assume a higher incline than at the opening 22, thus the flooring 15 within such triangle is such as to form a trough towards the opening or passageway, and it will be readily seen that it will make 40 it very difficult to hold three balls behind the partitions while working on the opposite corner, yet it can be done, but only with patience and persistency.

The floor 15 after the partitions have been 45 secured thereto has a daub of paste in the center which holds it securely to the bottom of the container and at the same time by reason of it being placed in the center as noted it causes the rest of the flooring outside 50 of the partitions to assume its intended pitch or slants from all directions towards the center, and thereby the center of the floor being pasted to the bottom, causes the small balls to always rest in the center. By 55 reason of the pillows at the opposite ends, and the slotted portions being free to assume any desired angle it also causes the corners 28 and 29 to be just slightly higher than that portion that is immediately pasted to 60 the floor of the container, this will cause a pitch or slant of the floor from all corners toward the center as is shown in Figure 1.

The sole object in cutting slits in the floor is not so much for the purpose of setting 65 the partitions therein, as to give the floor-

ing on each side of the same a peculiar twisting curvature or inclination, which with the assistance of the pillows 13 and 14, causes the inclination within the compartments as well as without. The flooring by 70 reason of being secured to the partitions at various heights causes the same to pitch or incline; especially is this so when it is remembered that the center of the flooring is pasted to the bottom of the container, which 75 causes the opposite corners, to those provided with partitions, to incline also.

Of course, it will be understood that the arrangement exists in form shown in Figure 5, wherein it is necessary to positively secure the flooring at the proper heights by adhesives or other means when the partitions are placed therein, as the extensions prevent the lower ends of the partitions touching the bottom of the container, thus 80 it will be seen that this is the only way that the floor could possibly get the necessary smooth rolling uneven surface for the balls to roll over. It is necessary to paste the flooring to one or both sides of the partitions 85 when the partitions do not touch the bottom of the container, at other times it may only be necessary to paste on one side, especially is this true when the pillows are used.

As shown in Figure 5, the floor 15¹ has 90 downwardly supporting extensions on all sides, such extensions being so cut as to not only give the floor 15¹ the proper angular pitch, the slits for the partitions being so located as shown in Figs. 1, 2 and 3 and free 100 from the side extensions, thus leaving the triangular portion behind the positions to assume any angular position without interfering in any way with the desired object of the invention. It will be here noted that 105 by reason of such extensions and their angular lines, it does not require pillows or other additions as the extensions on the floor accomplish the same purpose to the same extent as that shown in the other 110 figures.

Again, it may be found advisable to have the fore partition made in one piece and be provided with an entrance or opening therethrough, while I have constructed some so provided, have decided that where separate partitions are provided it affords for the spherical bodies resilient means whereby the many balls are kept going from one side to another by the elasticity of the partitions 120 themselves.

The invention may be attained in many ways as has been noted, for instance, it is desirable that the partitions be secured to the floor from one side only after they have 125 been properly adjusted in their respective slots, this is done first, so that the flooring within the corner of the triangle will assume a different slant from that on the other side of said partition by being placed 130

on the pillows and secondly where no pillow is used, the two front partitions are fitted into their respective slits in the floor so that a certain portion of the same extends below the floor as well as above, again when this is done all three partitions may be shaped on their lower end so as to sustain and give the flooring within and without the triangle the desired slant that it has when the pillow is used. It has been found more advantageous to make separate partitions as by doing so they are more resilient and cause the spheres to bounce on coming in contact with them, whereas if the front partition had a passage way cut into it, the partitions by reason of their length, would deaden the activities of the spheres.

In accordance with the provision of the patent statutes, I have herein described the principal forms of my invention which I now consider to represent the best embodiment thereof, but I desire to have it understood that the various forms are only illustrative and that the invention can be carried out in other ways other than those described, but all are intended to come within the scope of the claims. Also while the design of the game is rectangular, it may be changed or altered to meet the particular requirements without interfering in any way with the general results for which the puzzle or game was designed.

What I claim as new is:

1. A game or toy for amusement purposes comprising a rectangular container provided with a smooth rolling uneven floor, of a plurality of resilient partitions secured to the floor forming compartments in opposite corners, spherical bodies therein and a transparent top for said container.

2. In combination with a container, of a separate floor therein having a smooth twisting uneven surface provided with a plurality of resilient partitions forming compartments in opposite corners, the flooring within said compartments differing in pitch to that of the outer, spherical bodies adapted to roll about said floor and be confined within opposite corners.

3. A game or toy having a smooth twisting uneven surface provided with a plurality of resilient partitions extending into slots in the floor to form an enclosure, the rolling pitching floor surfaces within and without the compartment differing, the front partitions being so spaced as to form a central opening, another of such partitions located in the rear and in line with said opening, to intercept the passage of the spherical bodies, and a closure for the container.

4. In combination with a receptacle comprising a bottom, sides and top, a floor suitable supported therein to give it a smooth rolling undulated surface, spaced partitions

provided in opposite corners to form compartments, and a plurality of balls therein adapted to be corralled and held within such partitions in opposite corners.

5. In combination with a container provided with a transparent top, a floor within the same provided with cuts or slits to receive and hold a plurality of partitions, said partitions extending above and below the slits in said floor, one set of partitions placed opposite the other, each set provided with an opening, and plurality of spherical bodies therein.

6. The combination with a receptacle, of a separate floor therefor, means for elevating certain portions of the same, of front and rear partitions opposite each other, each of the front partitions provided with an opening, back partitions in the path of the openings, spherical bodies to be corralled behind each set of partitions, and a transparent cover for said receptacle.

7. A game or toy having certain portions of its floor pitch towards the center, partitions secured to and extending above and below the floor, passageways in the outer partitions for the passage of the spherical bodies therethrough, the said flooring within the partitions pitching towards the passageways, and a container having a transparent face.

8. A game or toy having parts of its floor rest on pillows, partitions arranged in opposite corners, the flooring behind said partitions adapted to assume a different angle from that in front, spherical bodies adapted to roll about the floor and about the partitions, and a container having a transparent face secured thereto.

9. A game or toy consisting of a container, pillows suitably located therein, a flooring provided with partitions and the former secured to the container, said pillows arranged to give the flooring within the partitions a pitch towards the passageway, and that outside towards the center, of spherical bodies adapted to pass between the several partitions, and a container having a base with suitable sides supporting a transparent face.

10. A game or toy consisting of a rectangular container, of supports to hold the floor at a suitable distance from the bottom at various points, said flooring provided with partitions to form corrals for the spherical bodies at opposite points, passageways through certain of the partitions, the flooring within the corrals sloping towards the opening, the flooring outside of the corrals sloping towards the center, said container having a bottom, side walls to support and have secured thereto a transparent face.

11. In a game or toy, the combination with a container, a floor within provided with

apertures or slots to receive the partitions, means for giving said floor a variety of slants about the interior and exterior of the partitions, and spherical bodies adapted to roll about said floor and be corralled equally behind each set of partitions.

12. The combination with a closed container having therein a smooth rolling undulated floor surface, two partitioned compartments one in each opposite corners, each compartment provided with a plurality of spaced resilient partitions, the flooring within inclined differently from that without, the front partitions spaced to form an opening while the rear partition obstructs such opening, and a plurality of balls adapted to be corralled within the partitions on opposite sides.

13. In a puzzle of the character described, a floor having a smooth undulated surface, partitions in the corners thereof forming triangular compartments, additional parti-

tions therein obstructing the entrance of said compartment, the flooring within said compartments pitching from a plurality of points therein, and a plurality of balls adapted to be corralled and held behind said partitions and within said compartment.

14. In a puzzle, a floor having inclined portions at all corners thereof, partitions in two of said corners to form compartments, and a plurality of balls adapted to be corralled and held in said compartments.

15. In a puzzle of the character described, a flooring having a smooth undulated surface, partitions in opposite corners thereof, said flooring secured to the side of said partitions, compartments formed by said partitions, and a plurality of balls adapted to be corralled and held behind such partitions.

In testimony whereof he affixes his signature.

T. HARVEY POPE.
